[57] **CLAIM**

The ornamental design for a multiple position counter unit, as shown and described.

DESCRIPTION

FIG. 1 is a front perspective view of a multiple position counter unit showing our design;

FIG. 2 is a right side elevational view thereof;

FIG. 3 is a rear elevational view;

FIG. 4 is a fragmentary top plan view illustrating a typical junction between abutting modules in greater detail; and

FIG. 5 is a fragmentary front elevational view illustrating a typical junction between abutting modules likewise in greater detail.

The side of the multiple position counter unit not shown is a mirror image of the side shown in FIG. 2.
